United States Patent Office

Des. 185,727
Patented July 21, 1959

185,727

MOP HEAD

Irving A. Yamen, Hayward, Calif., and William W. Smith, Denver, Colo., assignors to Dust-Tex Corporation, Denver, Colo., a corporation of Colorado

Application August 14, 1957, Serial No. 47,358

Term of patent 14 years

(Cl. D9—2)

Fig. 1

The essential features of our design reside in the portions shown in full lines.

We claim:

The ornamental design for a mop head, as shown and described.
